ATTORNEY.

UNITED STATES PATENT OFFICE.

EDWARD KILBURN ROBINSON, OF BELMONT, MASSACHUSETTS.

BOOKBINDING.

Application filed March 20, 1920. Serial No. 367,547.

To all whom it may concern:

Be it known that I, EDWARD K. ROBINSON, a citizen of the United States, residing at Belmont, in the county of Middlesex and 5 Commonwealth of Massachusetts, have invented certain new and useful Improvements in Bookbinding.

The object of my invention is to provide for the binding of books, pamphlets or other 10 similar material in such a manner that pages of tracing paper may be placed conveniently over printed pages of pictures, maps, diagrams or designs.

In a book bound in accordance with my 15 invention there may be combined with a printed book or pamphlet sheets of tracing paper or writing paper so that they may be folded over the pages of the book or pamphlet for the purpose of tracing pictures, 20 maps, diagrams or designs or for making original drawings or for writing notes.

In the accompanying drawing is shown a book bound in accordance with my invention. A cover of paper, cloth or other suitable 25 material is shown by *e*, *e*¹, *e*². Bound or attached along the line *a b* is one set of pages *f f*¹, which can be turned to the left or to the right. Bound or attached along the line *c d* is another set of pages *g*, *g*¹, *g*², 30 which can also be turned to the left or to the right. The binding may be done by means of thread, wire or any other common means of permanent attachment to a book cover, or the sets of pages may be 35 bound separate from the cover and attached to the cover by any temporary means, such as an envelope pocket into which a strip is inserted to hold the pages in position.

For the purpose of map drawing and 40 study, picture tracing, etc., the set of pages *g*, *g*¹, *g*² may be pages of tracing paper bound or attached to the cover at *c d*. Bound or attached at *a b* may be printed pages, text being on the left hand pages and printed 45 maps, pictures or the like on right hand pages. A page of the tracing paper *g* may thus be laid over the printed map or picture in the manner shown in the drawing, and the user of the device can then make 50 his own drawing on the tracing paper. In map study additional features may be called for by directions on the printed page. After one tracing page is thus used it may be

turned to the right, at *g*⁴, and another brought up from the position *g*² under the 55 pages *f*¹ and placed in position over any desired page *f*¹, whereupon this new tracing page is ready for use.

When not in use the pages *g*, *g*¹, *g*², together with the cover portion *e*², are all 60 folded together in position *g*² and the book is closed by turning pages *f* and cover portion *e* to the right.

A book embodying my invention is scarcely larger than an ordinary book of 65 the same size paper page, except for a slight additional width and the thickness of the pages bound at *c d*.

What I claim as new and desire to secure by Letters Patent is:—

1. A tracing book consisting of a cover, 70 a set of leaves bound therein containing printed text on the pages lying at one side as the book is opened, and matter to be traced on the opposite pages, and a set of 75 leaves of tracing paper attached to said cover along a line such that any page of the tracing paper can be superimposed over any page of the matter to be traced.

2. A tracing book consisting of a cover, 80 a set of leaves bound therein containing printed text on the pages lying at one side as the book is opened, and matter to be traced on the opposite pages, and a set of 85 leaves of tracing paper attached to said cover on a line parallel to the line of attachment of said first set of pages and at a distance from said line of attachment approximately equal to the width of one of said pages.

3. An educational device consisting of a book having a cover, a set of pages bound 90 therein containing printed text and matter to be traced, and a set of pages of tracing paper bound therein on a line parallel to 95 the line of attachment of the first set and at a distance from said line of attachment approximately equal to the width of one of said pages of printed text.

In testimony whereof I have hereunto set 100 my name in the presence of two witnesses this 16th day of March, 1920.

EDWARD KILBURN ROBINSON.
